ATTORNEYS.

UNITED STATES PATENT OFFICE

153,487

DESIGN FOR AN ELECTRIC WALL HEATER

Frederick B. Adam, Huntleigh Village, Mo., assignor to Frank Adam Electric Company, St. Louis, Mo., a corporation of Missouri

Application January 20, 1947, Serial No. 136,261

Term of patent 14 years

(Cl. D81—10)

To all whom it may concern:

Be it known that I, Frederick B. Adam, a citizen of the United States, residing at Huntleigh Village, in the county of St. Louis, State of Missouri, have invented a new, original, and ornamental Design for an Electric Wall Heater, of which the following is a specification, reference being had to the accompanying drawing, forming part thereof.

Figure 1 is a front perspective of an electric wall heater, showing my new design.

Figure 2 is a view in side elevation of the same.

Figure 3 is an end view of the same.

I claim:

The ornamental design for an electric wall heater, as shown.

FREDERICK B. ADAM.
